(57) **CLAIM**

The ornamental design for a combined wall mounted debris catcher and materials holder, as shown and described.

DESCRIPTION

FIG. 1 is a front plan view of a first embodiment of a combined wall mounted debris catcher and materials holder; FIG. 2 is a rear plan view thereof;

FIG. 3 is a right side view thereof;

FIG. 4 is a left side view thereof;

FIG. 5 is a top plan view thereof;

FIG. 6 is a bottom plan view thereof;

FIG. 7 is a front plan view of a second embodiment of a combined wall mounted debris catcher and materials holder;

FIG. 8 is a rear plan view thereof;

FIG. 9 is a right side view thereof;

FIG. 10 is a left side view thereof;

FIG. 11 is a top plan view thereof;

FIG. 12 is a bottom plan view thereof;

FIG. 13 is a front plan view of a third embodiment of a combined wall mounted debris catcher and materials holder;

FIG. 14 is a rear plan view thereof;

FIG. 15 is a right side view thereof;

FIG. 16 is a left side view thereof;

FIG. 17 is a top plan view thereof;

FIG. 18 is a bottom plan view thereof;

FIG. 19 is a front plan view of a fourth embodiment of a combined wall mounted debris catcher and materials holder;

FIG. 20 is a rear plan view thereof;

FIG. 21 is a right side view thereof;

FIG. 22 is a left side view thereof;

FIG. 23 is a top plan view thereof; and,

FIG. 24 is a bottom plan view thereof.
